Primary Examiner — Garth Rademaker*Assistant Examiner* — Melanie Pellegrini(74) *Attorney, Agent, or Firm* — Benjamin A. Balser; Balser & Grell IP Law(57) **CLAIM**

The ornamental design for a single drop earring, as shown and described.

DESCRIPTION

The sole FIGURE is a front perspective view of a single drop earring showing my new design.

The broken lines shown in the drawings illustrate portions of the single drop earring that form no part of the claimed design.
